2,325,621

HIGH TENSION SIGN INSULATOR AND
ATTACHING MEANS THEREFOR

Samuel C. Miller, New York, N. Y.

Original application October 5, 1936, Serial No.
103,964. Divided and this application October
25, 1940, Serial No. 362,709

10 Claims. (Cl. 173—339)

This application is a division of my application Serial No. 103,964, filed October 5, 1936, which was issued on October 29, 1940, as Patent No. 2,219,327.

My invention relates to an insulator construction and attaching means therefor, particularly useful in connection with high tension illuminants, such as neon tube assemblies. More particularly my invention relates to insulators of the character and for the purpose mentioned, in the form of housings or collars and attaching means therefor, particularly where the insulating material constitutes glass of the low expansion borosilicate type, such as disclosed in Sullivan and Taylor Patent No. 1,304,623.

While glass, specifically that of the type above referred to, provides an excellent insulator, of proper dielectric qualities and density or freedom from porosity, its use for purposes contemplated by me is not commercially feasible because this glass in its formation for insulators, must be shaped at extremely high temperatures by casting operations utilizing a plunger type of core. Accordingly, the incorporation into the mold parts of mold configurations which are to serve as the means for attaching the insulators in position, of the character heretofore employed, is not suitable where glass of the character referred to constitutes the insulator material.

In the utilization of insulators of the character described, which are arranged to be assembled in connection with sign frames of the neon tube type, these frames frequently take on considerable proportions and the attachment of insulators necessitates the cooperation of two men—one to locate the insulator from the front face of the frame and the other to fasten it from the rear face of the frame.

Accordingly, one phase of my invention resides in the provision of fastening means for insulators of the character described, which are capable of attachment from the front face of the sign frame and the location and fastening of the same from that position.

A further object of my invention resides in the provision of attaching means for insulators which permit of front face attachment and location, and of such form and construction to permit the employment of glass of the character described.

A further object of my invention is to provide a form of insulator for the purposes described, employing glass and attaching means permitting the location and attachment of the insulator from the front face of the sign framework, avoiding the introduction of attaching means which will

reduce the efficiency of the insulator for its intended purpose, particularly in high tension electrical installations for illuminants of the character described.

Thus, my invention has for its object the provision of insulators permitting the employment of glass of the character mentioned, while retaining all the efficient operating conditions attained by this form of insulating material.

To attain the aforementioned objects and such further objects as may appear herein or be hereinafter pointed out, I make reference to the accompanying drawing, forming a part hereof, in which

15 Figure 1 is a fragmentary sectional view of one embodiment of my invention, of an insulator and attaching means;

Figure 2 is a section taken on the line 2—2 of Figure 1;

20 Figure 3 is a fragmentary sectional view of another embodiment of my invention;

Figure 4 is a fragmentary plan view of the device illustrated in Figure 3, with the insulator removed;

25 Figure 5 is a section taken on the line 5—5 of Figure 4.

Making reference to the drawing, particularly Figures 1 and 2, I have illustrated an electrode housing insulator 10. This may preferably be 30 of the general configuration referred to in my Patent No. 2,046,960, granted July 7, 1936, in which the insulator housing serves as mounting means for the terminal and contact support of a high voltage electrical illuminating sign, such as a neon tube sign and which, with the exception of the attaching means herein more specifically described, may incorporate the features of such housing in all other respects.

Accordingly, the housing mentioned is arranged 35 to dispose a contact terminal 11 at the bottom of a central boring 12, opposite to the mouth of the housing. Adjacent to the mouth there is provided a peripheral flange 14. Inwardly spaced from the flange 14, there is formed a second abutment flange 15, in the form of a screw threaded portion, leaving a neck 16 forming a seat between the aforementioned flanges, which will be more particularly amplified hereafter.

The insulator just described is arranged to be 40 attached to the frame 17 of a neon tube construction and this is provided with an orifice 18, the dimensions whereof permit passage therethrough of the abutment flange 15 but are less than the maximum dimension of the flange 14, whereby this may abut the walls of the orifice 18.

The general configuration of the insulator housing thus described is particularly amenable to casing operations where glass is employed. Thus, the plunger type of core mechanism used in connection with molds for casting may readily be employed in that there are no fine or sharp corners, prohibitive in casing glass of the heat resisting type. The interior as well as the exterior configuration of the insulator just described being of extremely simple contour, the mold necessary for casting the glass may be used repeatedly, to make such glass available commercially for the intended purpose.

However, the simplicity of configuration, eliminating sharp corners, orifices, makes the attachment of this type of construction unsuitable for known types of attaching devices, especially in accordance with the primary objective of my invention, to provide attaching means permitting the insertion of the insulator member from the front face of the frame 17, through the orifice 18, without the assistance of someone to position the attaching means from the rear face of the frame 17, as is required in connection with the attaching collar shown in my patent aforementioned.

Accordingly, having provided the insulator member embodying the elements already described, either in a housing adapted to support the contact terminal assembly 11 or severed at an intermediate point along the line O, forming the collar, I will now refer to the attaching device contemplated by me in this application.

In Figures 1 and 2 I have illustrated an embodiment of my invention carrying out, to a certain degree, the objectives emphasized in respect of the configuration of the insulator and the attaching means of my previously filed application, of which the present application is a division.

In this embodiment, the insulator housing 19 has formed adjacent its mouth an outer flange 13 and an inner flange 14, tapering abruptly into the neck of the housing, adjacent which portion there is formed a screwthreaded portion 29, heretofore referred to as a second abutment flange 15. From this point downward, the exterior of the insulator tapers gradually, forming an exterior wall to the base of the insulator adjacent the contact terminal mounting means.

The pitch of the taper is such that the widest portion of the insulator may pass through the orifice 18 formed in the frame 17.

In connection with this construction, I provide a collar 30 which is split longitudinally at 31. This collar is formed with an outer flange 32 materially larger than the orifice 18. Spaced from the flange 32 there is formed an inner flange 33, thereby providing a neck portion 34. Beyond the flange 33, the collar is embossed with a screwthreaded section tapered to form with the threaded portion 29 on the insulator. In installing the insulator 19, the collar 30 is first positioned into the orifice 18, as more clearly shown in dotted lines in Figure 1 in contracted condition, passing the threaded portion 29 through the orifice until the inner flange 33 has passed the inner face of the frame 17, and the outer flange 32 abuts the outer face of the frame 17. In this position, the insulator is then disposed through the collar until the screw-threaded portion 29 engages the threaded portion of the collar. Screwthreading the insulator in relation to the collar progressively moves the insulator through the orifice and through the collar, accompanied by a spreading of the collar, due to the tapered con-

figuration of the screw-threaded portion 29 on the insulator, to the limit that the inner flange 32 is expanded to engage the walls of the orifice 18 in the final position, as shown in Figures 1 and 2. It will be observed that the portion 29 thereby provides a portion for directing the collar into engagement with the frame and into the seat formed by the neck 16. It will be understood that some instrumentality, such as a screw driver, may be inserted at the split portion 31 of the collar to hold the collar against relative rotation during the time that the insulator is rotated to effect the attaching action.

It will be observed that the construction in connection with Figures 1 and 2 embodies the features heretofore described, in respect of the insulator, by reason of its simple contours, making this construction particularly amenable to employ glass as an insulating material.

The insulator and attaching device just described have substantially all the features embodied in the same, as described in the construction of my prior parent application so far as the elimination of casting difficulties for the insulator. It will be understood, however, that though I have described the insulator and the attaching means as having particular novelty where the insulator material is made of glass, in that this is readily adapted for commercial casting operations where glass is employed, the features of my insulator and attaching devices may equally be employed with other insulating materials, such as porcelain, hard rubber and other insulating materials.

Furthermore, attachment of this insulator may be effected through the front face of the frame without requiring any assistance at a point to the inner or rear face of the frame 17.

It will also be observed that while I have described the insulator 19 of the general contour forming a receptacle or housing of the type illustrated in my aforementioned patent, the insulator may be formed as a collar by severing the portion adjacent the point indicated by the arrow O.

In Figures 3, 4 and 5 I have illustrated a still further embodiment of my invention, wherein the collar 10c having a boring or central orifice 12c is shaped exteriorly thereof to provide a flange 14c beyond which the collar extends into a neck portion 16c forming a seat, terminating into a screw-threaded portion 29c. It is preferred that the rear walls of the threads 35 be more abrupt than the forward thread walls 36, for purposes which will more clearly appear as this description proceeds.

Beyond the last convolution of the screw-threaded portion 29c, the exterior wall of the insulator is generally cylindrical or gradually tapers to its co-terminus B, where a collar is formed, though this may extend for an additional length to form a receptacle or housing, as shown in dotted lines in Figure 3 beyond the point B.

With an insulator of the character illustrated in Figure 3, I provide attaching means in the form of a spring clip 37 having spaced bowed branches 38 and 39 connected together by a loop 40. The clip 37 may be attached to the rear face of the frame 17 by a screw or similar attaching member 41, engaging the orifice 42 in the frame 17, thereby holding the clip 37 with the branches 38 and 39 transversely of the orifice 18. It will be understood that the clip 37 is formed of spring wire, with the branches 38 and 39 nor-

mainly disposed towards each other for a distance materially less than the diameter of the orifice 18, but sufficiently spaced apart to permit insertion of the base of the insulator 10c. When the clip 37 is disposed as described, I may affix the insulator 10c in position by passing its base through the orifice 18 until the screw-threaded portion 29c engages the branches 38 and 39. A rotation of the insulator 10c will draw the insulator in position until the flange 14c engages the front or outer face of the frame 17. It will be understood, however, that similar attachment may be made by pressing the insulator 10c to its full limit until the flange 14c engages the front or outer face of the frame 17. However, this might displace the branches 38 and 39 from their normal position, and accordingly, rotation, tending to draw the branches 38 and 39 in engagement with the inner face of the frame 17, is desirable. To effect the engaging action in a more positive way, I have formed the threads 29c so that the rear threaded wall is more abrupt than the forward threaded wall of the screw-threaded portion 29c. Thus, the forward threaded wall of the screw-threaded portion 29c may permit the insulator to act as camming portions in pressing the insulator into position between the branches 38 and 39, without rotation, yet permitting the seating of the branches 38 and 39 substantially flush with the inner face of the frame 17, upon rotation of the insulator.

It will thus be observed that though the construction described in Figures 3 and 4 may require a preliminary attachment of the attaching clip 37 in position on the rear face of the frame 11, thereafter the insulator may be positioned from the front face of the frame 17 without any assistance, at a point from the rear face of the frame.

However, in all of the embodiments illustrated, the configuration of the insulator is particularly amenable to casting operations employing heat-resisting glass as the material to be cast.

The form of the insulators described is particularly novel with the attaching devices, making for a high order of simplicity of installation, without sacrifice of efficiency in operation, under the most adverse weather conditions when employed in exterior installations.

Having thus described my invention and illustrated its use, what I claim as new and desire to secure by Letters Patent is:

1. A high voltage electrode readily removable insulator assembly for combination with a plate and insertable from the front face thereof through an orifice in said plate, said plate forming one element of the combination, an insulator forming another element, said insulator being formed adjacent one end with a flange larger than said orifice and with the other end thereof generally cylindrical and arranged to pass through said orifice, a second flanged portion formed on said insulator, the space therebetween forming an engageable seat, and attaching means thereon insertable from the front face of said plate through said orifice and having a portion larger than said orifice and arranged to lie on the exterior of said insulator and substantially encircle the same, said attaching means having a portion for engaging one of the elements and a portion for engaging the other element, to hold said elements in engagement with each other and entering said seat, said insulator having an additional portion which, upon rotation of said insulator, is operative for directing a portion of

said attaching means into engagement with one of the elements and into the engageable seat.

2. A high voltage electrode readily removable insulator assembly for combination with a plate and insertable from the front face thereof through an orifice in said plate, said plate forming one element of the combination, an insulator forming another element, said insulator being formed adjacent one end with a flange larger than said orifice and with the other end thereof generally cylindrical and arranged to pass through said orifice, a second flanged portion formed on said insulator, the space therebetween forming an engageable seat, and attaching means thereon insertable from the front face of said plate through said orifice and having a portion larger than said orifice and arranged to lie on the exterior of said insulator and substantially encircle the same, said attaching means having a portion for engaging one of the elements and a portion for engaging the other element, to hold said elements in engagement with each other and entering said seat, said insulator having an additional portion which, upon rotation of said insulator, is operative for directing a portion of said attaching means into engagement with one of the elements and into the engageable seat, said additional portion on said insulator comprising a screw threaded section, whereby the insulator may be removed in the direction of the front face by rotation thereof.

3. A high voltage electrode readily removable insulator assembly for combination with a plate and insertable from the front face thereof through an orifice in said plate, said plate forming one element of the combination, an insulator forming another element, said insulator being formed adjacent one end with a flange larger than said orifice and with the other end thereof generally cylindrical and arranged to pass through said orifice, a second flanged portion formed on said insulator, the space therebetween forming an engageable seat, and attaching means thereon insertable from the front face of said plate through said orifice and having a portion larger than said orifice and arranged to lie on the exterior of said insulator and substantially encircle the same, said attaching means having a portion for engaging one of the elements and a portion for engaging the other element, to hold said elements in engagement with each other and entering said seat, said insulator having an additional portion which, upon rotation of said insulator, is operative for directing a portion of said attaching means into engagement with one of the elements and into the engageable seat, said attaching means comprising a resiliently formed element including a portion adapted to enter said seat on said insulator and prevent withdrawal of said insulator from said orifice.

4. A high voltage electrode readily removable insulator assembly for combination with a plate and insertable from the front face thereof through an orifice in said plate, said plate forming one element of the combination, an insulator forming another element, said insulator being formed adjacent one end with a flange larger than said orifice and with the other end thereof generally cylindrical and arranged to pass through said orifice, a second flange portion formed on said insulator, the space therebetween forming an engageable seat, attaching means thereon arranged to lie on the exterior of said insulator and substantially encircle the same,

said attaching means comprising a portion for engaging the exterior of said plate and a portion for engaging the interior of said plate, said attaching means being insertable from the front face of said plate, said insulator having a portion which, upon rotation of said insulator, is operative for directing said attaching means into the engaging position aforesaid and into the engageable seat formed between said flanged portions of said insulator.

5. A high voltage electrode readily removable insulator assembly for combination with a plate and insertable from the front face thereof through an orifice in said plate, said plate forming one element of the combination, an insulator forming another element of the combination, said insulator being formed adjacent one end with a flange larger than said orifice, and with the other end thereof generally cylindrical and arranged to pass through said orifice, a second flange portion formed on said insulator, the space therebetween providing a neck forming an engageable seat, and attaching means thereon arranged to be inserted through the front face of said plate, said attaching means having a screw-threaded portion and flanged portions arranged to lie on the exterior and interior portions of said plate, said insulator being formed with a screw-threaded portion on the exterior surface thereof, formed to direct said attaching means into engagement with the plate upon rotation of said insulator.

6. A high voltage electrode readily removable insulator assembly for combination with a plate and insertable from the front face thereof through an orifice in said plate, said plate forming one element of the combination, an insulator forming another element of the combination, said insulator being formed adjacent one end with a flange larger than said orifice and with the other end thereof arranged to pass through said orifice, a screw threaded portion formed on said insulator adapted to pass through said orifice and attaching means arranged to lie on the exterior surface of said insulator and engageable by said screw threaded portion on said insulator, said attaching means including a flanged sleeve split along the length thereof, to be insertable through the orifice of said plate and expandable to conform to said orifice and including flanged portions arranged to engage the exterior and interior surfaces about said orifice, said insulator including a portion thereof formed to project said sleeved attaching means into engagement with said plate whereby the assembly may be attached from the front face of said plate and removed in that direction.

7. A high voltage electrode readily removable insulator assembly for combination with a plate and insertable from the front face thereof through an orifice in said plate, said insulator being formed adjacent one end with a flange larger than said orifice and with the other end thereof generally cylindrical and arranged to pass through said orifice, a threaded portion formed on said insulator adjacent said flanged portion, an attaching means comprising a collar split longitudinally thereof and formed with an outer flange larger than the orifice, spaced from an inner flange, said spaced flanges being arranged to engage the exterior and interior faces, respectively, of the orificed portion of said plate, said insulator being formed to position said collar

with the flanges thereof in the plate engaging positions aforesaid upon rotation thereof relative to said collar.

8. A high voltage electrode readily removable insulator assembly for combination with a plate and insertable from the front face thereof through an orifice in said plate, said insulator being formed adjacent one end with a flange larger than said orifice and with the other end thereof generally cylindrical and arranged to pass through said orifice, a threaded portion formed on said insulator adjacent said flanged portion, an attaching means comprising a collar split longitudinally thereof and formed with an outer flange larger than the orifice, spaced from an inner flange, said spaced flanges being arranged to engage the exterior and interior faces, respectively, of the orificed portion of said plate, said insulator being formed to position said collar with the flanges thereof in the plate engaging positions aforesaid upon rotation thereof relative to said collar, said collar including a screw threaded portion engageable by the screw threaded portion of said insulator.

25. A high voltage electrode readily removable insulator assembly for combination with a plate and insertable from the front face thereof through an orifice in said plate, an insulator formed adjacent one end with a flange larger than said orifice and with the other end thereof generally cylindrical and arranged to pass through said orifice and attaching means comprising a collar split longitudinally thereof and formed with an outer flange materially larger than the orifice, an inner flange formed on said collar providing a neck portion adapted to engage, respectively, the exterior and interior faces of said frame, a screw threaded section formed on said collar, said insulator being formed with a screw threaded portion adjacent said flange adapted to engage the screw threaded section of said collar and, upon rotation, position the flanges of said collar into engagement with said plate on the exterior and interior portions thereof, to hold said insulator and collar in removable position on said plate.

10. A high voltage electrode readily removable insulator assembly for combination with a plate and insertable from the front face thereof through an orifice in said plate, an insulator formed adjacent one end with a flange larger than said orifice and with the other end thereof generally cylindrical and arranged to pass through said orifice and attaching means comprising a collar split longitudinally thereof and formed with an outer flange materially larger than the orifice, an inner flange formed on said collar providing a neck portion adapted to engage, respectively, the exterior and interior faces of said frame, a screw threaded section formed on said collar, said insulator being formed with a screw threaded portion adjacent said flange adapted to engage the screw threaded section of said collar and, upon rotation, position the flanges of said collar into engagement with said plate on the exterior and interior portions thereof, to hold said insulator and collar in removable position on said plate; said threaded portions on said collar and insulator being tapered whereby said collar is affixed in position expansively.

SAMUEL C. MILLER.
